UNITED STATES PATENT OFFICE.

EMMIT G. LATTA, OF SYRACUSE, NEW YORK; FIRST TRUST AND DEPOSIT COMPANY, ADMINISTRATOR OF SAID EMMIT G. LATTA, DECEASED, ASSIGNOR TO UNDERWOOD TYPEWRITER COMPANY, A CORPORATION OF DELAWARE.

TYPEWRITING MACHINE.

Application filed March 18, 1920. Serial No. 366,807.

This invention relates to the carriages of typewriting machines and particularly to improvements in the platen and its operating mechanism.

5 One object of the invention is to improve the carriage of typewriting machines by making its various attachments more compact without lessening their efficiency, to locate such parts in desirable positions for use, 10 and to make them so that they can be condensed, or reduced in dimensions for encasing the machine when traveling. The improvements are especially desirable for collapsible or portable typewriting machines, 15 such, for instance, as that disclosed in my copending application Serial No. 319,609, filed August 25th, 1919 (now Patent No. 1,410,764, of March 28, 1922), but the invention is not restricted to use on portable typewriters, and can be used on standard machines.

Other objects are to adapt a carriage with an ordinary rotary platen to take wider paper than others of no greater total length, 25 and to do this with platen knobs operatively located at suitable distances from the ends of the carriage; also to accomplish this result in a construction having a horizontally swinging line space lever of approved form 30 and location, a line space adjusting device and carriage release lever in convenient positions for use; also to mount all of said parts on the carriage so that they can assume lower relative positions when the machine is encased; also to make the platen detachable from the carriage without the use 35 of tools; also to release the carriage from its escapement when the machine is encased.

Other objects are to provide the platen 40 with a telescoping shaft, and to make the platen detachable from the carriage by novel means without the use of tools, and whereby the platen may be removed either with the line space mechanism attached 45 thereto or remaining on the carriage as may be desirable or necessary; and to improve the construction of typewriting machine carriages and mechanisms in the other respects hereinafter described and set forth in the 50 claims.

In the accompanying drawings:

Fig. 1 is a side elevation partly broken away of a portable typewriting machine embodying the invention.

Fig. 2 is a front elevation of the platen 55 carriage removed from the machine, and showing the parts in their operative positions.

Fig. 3 is a top plan view thereof.

Fig. 4 is a longitudinal sectional elevation 60 of the platen and line space mechanism and showing the parts of the platen shaft in their collapsed or inoperative positions.

Fig. 5 is a longitudinal horizontal section 65 of the platen detached from the carriage.

Fig. 6 is a fragmentary view similar to Fig. 4 but showing the parts of the platen shaft in operative position.

Fig. 7 is a side elevation of the right hand 70 end of the carriage.

In this application the invention is shown and described in connection with a portable typewriting machine of the sort disclosed in my copending application above mentioned.

In this machine all the operative parts are 75 mounted on a hollow main frame A which forms the lower part of the enclosing case for the machine. The bottom 11 of this frame has front and rear portions extending 80 at an obtuse angle to each other to enable the frame to be supported either in an inclined or a horizontal position. B represents the upper or cover part of the enclosing case. The edges of the side walls 18 thereof are shaped to fit the bent upper and 85 lower edges of raised panels 19 on the sides of the main frame. When the cover is in the position shown in Fig. 1 all the operative parts of the machine are disposed between two parallel planes indicated by the 90 lines a—b and c—d. The cover is adapted to be removed and placed in an inverted position on a support, and the frame A placed on the cover with the lower edges of the 95 panels 19 resting on the edges of the sides 18 of the cover. The cover then forms a base by which the machine is supported in an inclined operative position, and the planes a—b and c—d will incline upwardly and rearwardly at the angle represented by 100 the dotted line a—b in Fig. 7.

20 represents the usual carriage guide track, which, as shown, is secured at its ends to the side walls 14 of the main frame. The carriage C as usual comprises a track bar 105 25 movable along the guide track 20 on balls 26, and end plates 27 and 28 rigidly secured to the opposite ends of the bar 25.

The end plates are provided with bearing seats for the shaft of the platen D. E, E represents the usual paper feed rolls, F is the carriage escapement wheel, G the rack bar and H the pinion meshing with the rack bar for controlling the letter space movements of the carriage. The end plates 27 and 28 of the carriage C are substantially alike, each having a laterally offset recessed part 29 and upright front and rear extensions 30 and 31 respectively. A scale bar 35 connects the two front extensions 30.

The end wall 36 of each recessed part is provided with an upwardly and rearwardly extending, open ended slot 37 and the circular bottoms of these slots are enlarged to form bearing seats for the shaft of the platen D. The bottom of the recess 29 is concentric with these seats. A carriage release lever 40 pivotally mounted inside of the end plate 27 on the end wall of the recess 29 thereof, and an arm 41 similarly pivoted on the end plate 28, are secured at their rear ends to the rack bar G, so that the rack bar G may be lifted out of mesh with its pinion H to permit the carriage C to be set back for starting a new line by depressing the front end 42 of the release lever 40.

The platen D comprises the usual hollow cylindrical core 45 of wood or the like, an outer resilient covering 46 and end disks 47, 48 secured to the opposite ends of the core by screws 49 and mounted on a platen shaft J.

The platen shaft J, see Figs. 4-6, is telescopic, comprising a middle tubular section 50 and opposite end sections 51, 52 formed by rods adapted to slide in the tube 50 from outer operative positions to inner inoperative positions. The tube 50 is provided near its opposite ends with longitudinal slots 55, 56, and cross pins 57 extending through the inner ends of the end sections 51, 52 and entering the slots 55, 56, guide and limit the movements of the end sections in the tube. Finger wheels or knobs 58 and 59 are secured to the outer ends of the end sections. The operative positions of these finger wheels and of the end sections of the shaft J are shown in Figs. 2, 3, and 6, also by dotted lines in Fig. 4. In this position the finger wheels are located outwardly away from the end plates of the carriage where they can be conveniently grasped and operated. They are held in this position with the pins 57 against the outer ends of the slots 55, 56 by a helical spring 60 in the tube 50 and engaging the inner ends of the end sections.

When it is desired to reduce the width of the machine the end sections 51, 52 of the platen shaft are pushed inwardly by means of the finger wheels to the positions shown in Figs. 4 and 5 and there locked by turning the finger wheels in opposite directions to cause

the cross pins 57 to enter lateral seats 61 at the inner ends of the slots 55, 56, in which they will be retained by the pressure of the spring 60.

The finger wheels 58, 59, as shown in Fig. 4, are preferably in the form of cupped sheet metal stampings having inwardly extending rim flanges. When the finger wheels are pushed in to their inner positions the wheel 58 will enter the recess of the carriage end plate 27 with its outer end flush with the outer side of the end plate. The other finger wheel 59 is of a diameter large enough for its rim flange to surround the outwardly extending recessed portion 29 of the other end plate 28 when the wheel is shoved inwardly. Preferably the finger wheel 58 is screwed on the shaft section 51 while the other finger wheel 59 is welded on its shaft section 52.

Means are provided to permit the platen D to be readily removed from the carriage. In the preferred construction for this purpose the end sections 51, 52 of the platen shaft are flattened or notched on opposite sides as at 63, Figs. 4-7, so that if the end sections are pressed inwardly until these notches 63 register with the slots 37 in the carriage end plates and turned to align the notches 63 with the slots, then the shaft can be removed through the slots 37. In the normal position of the end sections of the shaft, the engagement of their cylindrical portions in the circular bearing seats prevents accidental disengagement of the platen.

The line spacing mechanism includes a ratchet wheel 65 which is loosely journaled on the left hand end of the tube 50 of the platen shaft between the adjacent end disk 48 of the platen and a screw sleeve 67 which is screwed on the threaded outer end of the tube 50. The ratchet wheel can be turned independently of the platen, but is held in frictional connection therewith by suitable means, such as a spring washer 66 between the ratchet wheel and platen end plate and having radial spring arms 67a. The sleeve 67 has an inturned outer end adapted to engage the extreme end of the tube 50 to prevent the ratchet wheel from being clamped too tightly. The ratchet wheel 65 is therefore releasably or frictionally held by the washer 66 in such manner as to permit it to turn with or independently of the platen when so desired.

The ratchet wheel 65 is provided with an annular series of holes 70, and a locking pin 71, rigidly secured to the end section 52 of the platen shaft, is adapted, when said section is moved to its outer operative position, to enter one of the holes 70 and lock the ratchet wheel to the platen so that the rotation of the ratchet wheel will then be imparted to the platen. In the construction shown in the drawings the locking pin 71

is rigid with a sleeve 72 which is adapted to slide on the tube 50 and is secured to the inner end of the end section 52 by the cross pin 57. A hole 73 in the end disk 48 of the 5 platen permits the passage of the locking pin therethrough for engagement with the ratchet wheel. Any other suitable construction may be used to provide a releasable connection between the platen shaft J and the 10 ratchet wheel 65.

The platen D and platen shaft J may be assembled as follows:

The end disk 48 is first brazed or otherwise rigidly secured to the tube 50 of the 15 platen shaft and the spring washer 66, ratchet wheel 65 and sleeve 67 are slipped on the end section 52, and this section, to the outer end of which the finger wheel 59 has been brazed or otherwise rigidly secured, 20 is now inserted into the tube 50 and the sleeve 72 is slipped over the opposite end of the tube 50 and secured to the inner end of the end section 52 by the cross pin 57. The coil spring 60 is next inserted and the 25 opposite end section 51 of the shaft inserted and secured by the other pin 57. The sleeve 67, ratchet wheel 65 and spring washer 66 are now moved outwardly against the finger wheel 59 to permit the end disk 48 to be 30 secured by screws to the platen core. The opposite end disk 47 is then secured on the adjacent end of the tube 50 preferably by screwing it on a thread on the tube, and it is then fastened to the platen core by screws. 35 The finger wheel 58 is simply screwed hard onto the threaded end of the shaft section 51.

K represents a line space lever, which 40 preferably has a forwardly projecting arm provided at its front end with a handle portion 80, and having a forked rear end 81 that straddles the platen shaft and is pivoted to a bracket L by screws 82, 83 arranged above and below the platen shaft 45 in the vertical plane thereof, so that the lever K can swing substantially horizontally. The bracket L is preferably formed as a single piece die casting and is disposed in the recess 29 of the carriage end plate 28 and forms a support for the various parts 50 of the line space mechanism. It is provided with an open ended slot 85, similar to the slots 37 of the carriage end plates, which receives the end section 52 of the 55 platen shaft and permits the shaft to pass in and out of its bearing seats in the end plates.

The upper edges of the carriage end plates 27, 28 are concentric with the axis of the 60 platen shaft and the bracket L has a lip 86 which overhangs and engages said concentric upper edge of the adjacent end plate as shown in Fig. 6. The lower pivot screw 83 for the lever K is formed with a flat 65 sided bottom extension 87 which projects

into a transverse slot 88 in the curved bottom of the part 29 of the carriage end plate 28 (see Fig. 6). This construction permits the bracket L to be rocked relative to the platen shaft and retains it in its proper location when the platen is removed. The bracket L can be turned to place its slot 85 in register with the slots 37 which will allow the bracket to remain on the carriage when removing the platen D, the platen 75 shaft passing out through said slots. If desired the bracket L and the line space mechanism carried thereby may be removed with the platen.

R represents the paper table which, as 80 usual, extends upwardly and rearwardly behind the platen. This table is rigidly secured to a shaft 120 journaled at its opposite ends in the rear portions 31 of the carriage end plates 27, 28. A downwardly 85 and forwardly projecting finger 121, fixed to the left hand end of this shaft, normally engages a rearwardly projecting lug 122 on the bracket L, and holds the bracket and the line space mechanism mounted thereon 90 in operative position. A coil spring 123, Fig. 3, at the opposite end of the shaft 120 holds the shaft and table in the normal position.

While the line spacing mechanism is 95 shown in the drawings for the purpose of illustrating the relation thereof and its assembly with the platen and carriage, its construction and operation has not been described in detail as it forms the subject matter of a separate application for patent.

When the parts of the machine are in operative position the free ends of the line space lever K, adjusting device P and carriage release lever 40 all project above the 105 line a—b and the upper edge of the paper table R projects rearwardly beyond the line b—d as shown in Fig. 7. When the rear part of the machine is lowered preparatory to encasing it for transportation, the lines 110 a—b and c—d become horizontal with the line space lever, adjusting device, carriage release lever and paper table R in the positions shown by dotted lines in Fig. 1.

To condense and encase the machine, the 115 end sections 51, 52 of the platen shaft J are pushed inwardly and there locked by turning the finger wheels as described. The inner edge of the left hand finger wheel at this time engages and moves the line space lever K inwardly so that its front end will not extend sideways beyond the vertical plane of the outer face of the finger wheel and the total length of the carriage is thereby reduced to the width of the keyboard. 120 The carriage is now moved to bring its center opposite the printing point and the cover part B of the enclosing casing is placed over the upper part of the machine and moved 125 forwardly. This pushes the upper edge of 130

the paper table forwardly, rocking the shaft 120 and swinging the finger 121 out of contact with the lug 122 of the bracket L, which leaves the bracket free to rock on the platen shaft. The cover B is now pressed downwardly and engages the front end of the line space lever, swinging it downwardly and rocking the bracket L and parts carried thereby in the same direction. In this movement the cover also engages the front end of the carriage release lever 40 and depresses it, thereby lifting the rack bar G out of engagement with its feed pinion H.

When the cover has been completely lowered into place on the main frame A, the above mentioned parts will occupy the positions shown in Fig. 1. The disengagement of the rack bar from the feed pinion prevents injury to the carriage escapement mechanism when transporting the machine.

To restore the machine to operative position the cover is removed, when the rack bar will be automatically re-engaged with the feed pinion by a coil spring 102. The front end of the line space lever is then lifted which will restore the line space mechanism to operative position. The paper table will then be returned to its proper position by its spring, and the finger 121 will engage the lug 122 on the bracket L and hold the line space mechanism in position.

By arranging the various parts and economizing space at the ends of the carriage as described, paper nine and one fourth inches wide can be used in a machine that can be enclosed in a case of no greater width than the keyboards of standard typewriters. Since the act of applying the cover to the machine causes the various shiftable parts mentioned to assume the positions shown in Fig. 1, there can be no danger of injury to any part by neglecting to shift it before applying the cover.

While, in the construction described, the carriage is mounted on a stationary frame and intended for use with a case shifting segment, manifestly the carriage could be mounted on a case shifting frame.

I claim as my invention:

1. In a typewriting machine, a rotary platen provided with a journal which is movable longitudinally toward and from the end of the platen, and a carriage having an end part provided with a bearing for the journal and with a slot opening out of the bearing through which the journal can pass sidewise into and out of the bearing when the journal is adjusted longitudinally to a predetermined abnormal position, relatively to said platen.

2. In a typewriting machine, a rotary platen provided with a journal which is movable longitudinally toward and from the end of the platen, a carriage having an end

part provided with a slotted bearing for the longitudinally movable journal which permits the journal to enter sidewise the bearing in one position of the journal relatively to said platen, said bearing and journal being shaped to permit the journal to move longitudinally in the bearing to the operative position and to prevent the removal of the journal when in said position, and means acting automatically to normally hold said journal in said operative position.

3. In a typewriting machine, a rotatable platen, a platen shaft having journal portions at the ends of the platen movable inwardly relatively to the platen for reducing the width of the machine, a carriage having end bearings in which said journals are adapted to rotate and slide longitudinally toward and from the ends of the platen, said bearings having side openings through which said journals can pass sidewise into and out of the bearings only when said journals are adjusted longitudinally to predetermined abnormal positions, and means for normally retaining said journals in positions in which they cannot be removed from the bearings.

4. In a typewriting machine, a platen, a carriage having an end part provided with a bearing seat for the platen shaft, a connecting slot of smaller diameter than the bearing seat, and a shaft movable longitudinally relatively to said platen and having a flat part normally out of line with said slot and adapted to pass through the slot laterally when the shaft is adjusted longitudinally relatively to said platen to locate the flat part thereof opposite the slot and parallel therewith.

5. In a typewriting machine, a platen provided with a tubular platen shaft having a helical spring therein, and a telescopic extension of the shaft normally held in extended position by the spring.

6. In a typewriting machine, a platen and shaft, a carriage having an end provided with an offset central part supporting one end of the platen shaft, said shaft having a sliding section, a platen knob mounted on said sliding section to move longitudinally relatively to said platen, means for holding the sliding section in either of two positions, and means normally tending to hold the sliding section in one of said positions.

7. In a typewriting machine, a platen and shaft, a carriage having an end provided with an offset central part forming a bearing for one end of the platen shaft, said shaft having a sliding section, a platen knob mounted on said sliding section and movable into and out of the offset end of the carriage, and means for locking the knob within the offset part of the carriage end.

8. In a typewriting machine, a rotary platen, a laterally adjustable platen knob, means for holding said knob against inde-

pendent rotation when in operative position, and means operated by turning the knob when in inoperative position for locking the knob in such inoperative position.

9. In a typewriting machine, a platen and shaft, a carriage having an end plate provided with an offset bearing portion for the platen shaft, and a platen knob constructed to inclose the offset portion of the end plate.

10. In a typewriting machine, a platen and shaft, and a carriage having end plates with offset portions forming bearings for the platen shaft, both of said offset portions facing the same way.

11. In a typewriting machine, a rotary platen having a shaft comprising a tubular central part, and telescopic end sections, and means for locking the end sections within the central part operated by turning the end sections in opposite directions.

12. In a typewriting machine, the combination of a platen having end journals, a carriage having end parts provided with laterally offset portions forming bearing supports for said journals, and finger wheels at opposite ends of the platen which are shiftable from operative outer positions beyond said bearing supports to inner positions in which the finger wheels and said offset bearing supports nest one within the other.

13. In a typewriting machine, the combination of a platen having end journals, a carriage having end parts provided with laterally offset portions forming bearing supports for said journals, and finger wheels at opposite ends of the platen which are shiftable inwardly toward the platen for reducing the width of the machine, one of said finger wheels being adapted to nest into the adjacent offset portion and the other offset portion being adapted to nest into the adjacent finger wheel.

14. In a typewriting machine, the combination of a platen having end journals, a carriage having end parts provided with laterally offset portions forming bearing supports for said journals, and finger wheels at opposite ends of the platen which are shiftable inwardly toward the platen for reducing the width of the machine, the finger wheel and offset bearing support at each end of the platen being constructed to nest one within the other.

15. In combination, a typewriting machine having a carriage, a carriage escapement, a device for releasing the carriage from the escapement, and a movable protecting cover for the machine, said release device and cover being arranged so that when the cover is moved to protecting position it will move said release device to release the carriage.

16. In combination, a typewriting ma-

chine having a carriage, a carriage escapement, a forwardly projecting release lever for releasing the carriage from the escapement, and a movable protecting cover for the machine, said release lever and cover being arranged so that when the cover is moved to protecting position it will move said release lever to release the carriage.

17. In combination, a typewriting machine having a carriage, a carriage escapement including a toothed rack, a release device for moving said rack to release the carriage, and a movable protecting cover for the machine, said release device and cover being arranged so that when the cover is moved to protecting position it will actuate said release device and move said rack to release the carriage.

18. In combination, a typewriting machine having a carriage, a carriage escapement, and means for both releasing the carriage from its escapement and restraining the released carriage from traveling movement, said releasing and restraining means including a machine-cover, which is effective for both purposes when it is moved to protecting position.

19. In combination, a typewriting machine having a carriage, a carriage escapement, a forwardly projecting release lever for releasing the carriage from the escapement, and a movable protecting cover for the machine, said release lever and cover being arranged so that when the cover is moved to protecting position it will move said release lever to release the carriage, but be held against traveling movement.

20. In combination, a typewriting machine having a carriage, a carriage escapement including a toothed rack, a release device for moving said rack to release the carriage, and a movable protecting cover for the machine, said release device and cover being arranged so that when the cover is moved to protecting position it will actuate said release device and move said rack to release the carriage, but be held against traveling movement.

21. In combination, a typewriting machine having a carriage, a carriage escapement including a toothed rack, a release device for relatively moving the carriage and said rack to release the engagement between the carriage and said rack, and a movable protecting cover for the machine, said release device and cover being arranged so that when the cover is moved to protecting position it will actuate said release device and release said engagement between the carriage and said rack to release the carriage from said engagement.

Witness my hand this 15th day of March, 1920.

EMMIT G. LATTA.
